(57) **CLAIM**

We claim the ornamental design for a display screen or portion thereof with icon, as shown and described.

DESCRIPTION

The file of this patent contains at least one drawing/photograph executed in color. Copies of this patent or patent application publication with color drawing(s) will be provided by the Office upon request and payment of the necessary fee.

FIGURE is the front view for a display screen or portion thereof with icon showing our new design.

The broken line in the FIGURE shows the display screen and forms no part of the claimed design.
